UNITED STATES PATENT OFFICE.

AXEL E. NORRMAN, OF HELSINGFORS, FINLAND.

SHUTTLE MOTION FOR LOOMS.

Application filed March 5, 1921, Serial No. 449,749, and in Great Britain March 29, 1920.

The purpose of this invention is to obtain an improved mechanism for transferring a shuttle quickly and effectively from one side of the loom through the shed opening to the other side.

In the present known and usually employed so-called negative shuttle motion (hereinafter referred to as negative shuttle motion), the transference of the shuttle is obtained by means of a picking arrangement which gives to the shuttle an amount of kinetic energy sufficient to effect the removal of the shuttle from one shuttle box to the corresponding box on the other side of the loom. The shuttle is thereby guided effectively only during the short time it travels in the box. In passing through the shed the shuttle is guided to some extent by the slay and the bottom shed on which it travels and also by the reed against which it is forced on account of the retardation of the slay motion in moving backwards during the pick and the subsequent acceleration of its motion forwards towards the cloth-fell.

It is evident that the warp threads that form the shed on which the shuttle is moving, are subjected to a severe strain, and very often single threads or groups of threads get broken. This happens especially if knots, loose ends, etc., get tangled in the warp so that the shed cannot open properly. In such a case the shuttle will break a great number of threads, and at the same time the direction of its travel will change to some extent, eventually the shuttle will be thrown out of the shed entirely.

Another method for obtaining the shuttle motion is to employ positively acting means that transfer the shuttle from one side of the loom through the shed opening to the other side. These means consist usually of similarly constructed arms on both sides of the loom, that move in opposite directions and that are provided with means, that carry and positively lock the shuttle during its motion. By these means the shuttle is first carried inward to the middle of the shed opening by one of said arms so that the shuttle is positively brought into contact with the locking means of the other shuttle carrying arm or holder. The locking means of the first named arm are released and corresponding locking means of the second arm or holder are brought into action. After this both arms are moved outwardly and the

shuttle is thereby taken over to the other side. The shuttle is then carried positively in the other direction when the arms again move in a similar way and the action of the catches is reversed.

The positive shuttle motions, although they removed many of the defects of the first mentioned negative shuttle motions are more complicated and cannot work as rapidly as the negative motions. Furthermore, the positive shuttle motion is divided through the transfer of the shuttle from one holder into another, when the velocity of the shuttle and the holders is practically zero, into two periods with first increasing and then decreasing velocity. The acceleration and the retardation of the shuttle motion result in forces that, acting on the shuttle, change direction four times during a single motion of the shuttle from one side of the loom to the other. The effect of the forces is especially injurious at the moment of transfer of the shuttle from one holder to the other, when the sudden changes in speed result in a heavy strain in the mechanism that lock the shuttle to the holders. These locking means, therefore, do not work quite reliably. The wear is very great and the mechanism consumes a great amount of power. For that reason the positive shuttle motions are mostly used only for certain slow running looms built for special purposes.

The object of the present invention is to devise an improved shuttle motion mechanism, which combines the advantages of the negative as well as the positive shuttle motions, but in which the disadvantages of both these mechanisms are eliminated. In other words the object of the invention is to produce a mechanism which is capable of running at a very fast speed and which at the same time makes it possible to transfer the shuttle through the shed without touching the warp threads and in such a way as to make it impossible for the shuttle to be thrown out of the shed.

A further object of the invention is to provide a shuttle motion mechanism, which is capable of working without heavy shocks and jars, so that the wear on the mechanism and the power required will be a minimum.

A still further object of the invention is to provide an improved shuttle motion mechanism of great simplicity, without hooks or catches, which grip the shuttle positively and

without any parts such as straps and pickers of leather or other material, that wear out quickly and that are subject to changes on account of varying temperature and humidity of the air.

These objects are obtained in a simple and efficient way by employing negative shuttle moving means that differ from the usually employed shuttle motion mechanisms or picking mechanisms by the fact that the shuttle is given the required velocity during a relatively longer time than is the case in the picking arrangements heretofore in use. For this purpose the stationary shuttle boxes 10 are changed into movable shuttle holders, or carriers hereafter referred to in a generic manner as shuttle holders which enclose the shuttle or part of the same and which act as pickers thereby transmitting the required 15 motion to the shuttle. The inertia of the moving shuttle is thereby of essential importance in transferring the shuttle from one holder to the other. In other words the kinetic energy inherent with the moving 20 shuttle accomplishes in this invention the complete transference of the shuttle from one holder to the other without the aid of mechanical means such as the complicated gripper and other transfer mechanisms employed in known positive shuttle motions.

The shuttle holders are guided along a path parallel to the weft through the shed opening but in opposite directions and without touching the upper or lower shed. The 25 shuttle holders are arranged similarly to the present picking mechanism one on each side of the loom and move during a beginning of the motion simultaneously in the direction towards each other and to an amount substantially half that of the shed crossing after which they move during the second 30 part of the weft or picking motion in a direction away from each other back to their original positions on both sides of the loom.

45 When the shed begins to open, the shuttle is outside the shed in a holder. As soon as the shed is sufficiently open the shuttle holders begin to move inwards. The velocity of the holders gradually increases and the 50 shuttle is carried forward with a corresponding velocity in the direction toward the other side of the loom. After attaining a maximum velocity the speed of the holders decreases to zero, when the shuttle holders have 55 reached a position relatively close to each other in the middle of the shed. After this the holders move back substantially in a similar way, so that the velocity of the holders increases to a maximum and decreases again to zero, as the shuttle holders 60 reach their original positions outside the shed on opposite sides of the loom. The mechanism is thereby arranged so that, when the velocity of the shuttle holders in the 65 inward motion is decreasing, the shuttle con-

tinues its motion forward on account of its inertia with a speed, which is only slightly less than the maximum speed of the holders depending upon the friction between the shuttle and shuttle holder. The shuttle is 70 thus transferred from one holder into another while the velocity of the holders changes from decreasing velocity forwards into increasing velocity backwards. The mechanism should be so arranged, that the 75 shuttle enters fully in the second holder after the same has begun its backward motion, so that, although the shuttle is moving with a great speed, the relative speed between the moving shuttle and moving shuttle holder is slight, so that the transfer of the shuttle from one holder to the other takes place without shock or jar. When the 80 holders are returning to their original positions the shuttle is taken over to the other side of the loom with the latter holder. Since the holder is then moving with a decreasing velocity the shuttle is forced on account of its kinetic energy against the holder and thus held more securely by the same. 85

When the shuttle holders during the following weft or picking motion are again moved the shuttle is transferred in the other direction. It will be noted that the shuttle obtains a forward and backward motion with a varying speed that increases and then decreases, the transfer of the shuttle being performed with a substantially uniform motion. The sudden shocks that the shuttle is subjected to in the usual picking motion are entirely eliminated, and the shuttle is guided effectively and cannot be thrown out of the shed. During the motion the holders and the shuttle move clear of the shed and the reed, so that the warp threads and the reed 100 are not subjected to injury or wear. Furthermore, it is evident that the shuttle motion is not dependent of the slay motion as is the case in the present looms. The shuttle motion mechanism can thus be constructed 105 independently of the mechanism for the slay motion.

Referring to accompanying drawing.

Figure 1 is a front elevation of the loom with the middle portion cut away, showing for the sake of clearness only those details that refer to the shuttle motion, while other parts of the loom such as the reed, the heddles and the heddle frames etc., are only indicated or not shown at all. Part of the 115 loom frame and the breast beam are also omitted so as not to interfere with the clearness of the drawing.

Figure 2 is an end view showing the arrangement for guiding the shuttle holders. 120 Only part of the frame and the most important details are shown.

Figure 3 is a section through the open 125 shed showing the relative positions of the shuttle, shuttle holder and reed.

Figure 4 is a section indicating the design of the track for guiding the shuttle holder.

Figure 5 is a front view and

Figure 6 a plan view of the shuttle.

5 Figure 7 is a section in larger scale showing the shuttle in the shuttle holder.

Referring to the drawings 1, 1 are the shuttle holders which are arranged parallel with the weft and designed so as to enclose 10 the shuttle or a part of the same. The inward ends of the shuttle holders are pointed as shown, so that in case of tangled up sheds they will push the warp threads aside with least possible strain or injury. 2 indicates 15 the shuttle in the holder on the right hand side of the loom.

The shuttle holders 1, 1 are each provided with an extension 3 which guides its respective holder along its central line during 20 movement through the shed. The guiding of said holders can be effected in various ways, one of which is indicated in the drawings. The extensions 3, 3 therefore constitute slides movable along tracks 6, 6 rigidly 25 connected to a frame part 5 extending on both sides of the loom. These tracks are positioned outside the shed in a manner which is determined according to the specific 30 type of loom concerned. They can advantageously be located as indicated in Figure 1 centrally of the shed and warp line. To allow for additional parts and also for other 35 reasons the location of the tracks may eventually be altered without departing from the principle of the invention. The tracks should however be of a length sufficient to permit the holders being efficaciously guided during the full extent of their travel.

The tracks can be designed as shown in 40 Figure 4. The extending portion of the holder consists of a rectangular plate 7, which is slidably mounted in slots 8 and 9, formed in the rigid frame part 5 which extends from one side of the loom to the other. 45 The frame 5 can be arranged so that the power for moving the shuttle holders can be transmitted independently of the power for operating the other parts of the loom such as for instance the slay. Also this detail will 50 possibly have to be altered in the design of different types of looms without thereby affecting the principle that is set forth in this specification.

Usually the shuttle motion mechanism in 55 looms is inter-related with the slay motion mechanism on account of the shuttle being guided during its motion through the shed by the slay and the reed. In this invention the shuttle does not need to be guided by these parts, and the shuttle motion mechanism can consequently be designed according to other purely practical considerations and eventually be entirely independent of the mechanism for transmitting the motion 60 to the slay and reed. Accordingly the frame

5 can be designed as stationary or movable in relation to the loom frame 25. The present practice is to build the shuttle boxes on the slay itself. The arrangement of the frame 5 as stationary or movable does not 70 interfere with the principle of the shuttle motion at all. It is, of course, understood that the frame 5 will have to be designed so as to allow for the necessary mechanism for beating up of the weft against the cloth-fell 75 by means of the reed 18 or any other means suitable for this purpose.

In the design that is indicated in Figures 1 and 2, the motion is transmitted to the shuttle holders by means of bell-crank levers 80 10 pivoted upon pins 11 in lateral extensions 12 of the frame 5. Connecting links 13 connect the levers 10 with the shuttle holder extensions 3, so that a swinging motion of the arms 10 is transmitted as a straight line 85 reciprocating motion to the shuttle holders. The small levers of the bell-crank levers are connected by means of links 15 to the arms 16. The shuttle holders move symmetrically 90 in relation to each other as hereinbefore mentioned. This motion can advantageously be obtained through connection of the arms 16 to a shaft 17, which is journalled in the loom frame 25 and extends from one side of the loom to the other. The required motion 95 of the shaft 17 is obtained preferably by means of a continuously revolving cam arrangement, so that a cam 19 coacting with a lever 20, transmits the motion to the holders 100 in one direction, while a cam 21 coacting with a lever 22 transmits the motion in the other direction. The levers 20 and 22 are in the usual way provided with antifriction rollers 23. The cams 19 and 21 rotate with the shaft 24 and thereby transmit in a simple 105 and efficient way a positive motion in both directions to the shuttle holders. The power may be transmitted directly to the cam-shaft or indirectly from some other revolving shaft of the loom. It will be noted that the levers 14 and 16 swing in different planes, so that the connecting pieces 15 must have joints 110 which will permit such movement.

On account of the shuttle being effectively 115 guided by the holders during its motion through the shed an improved arrangement of the shuttle can be obtained by giving the same a symmetrical form in relation to the shed in the way as indicated in Figure 5. The holders and the shuttle are thereby made 120 so that the shed opening is better utilized. The motion of the heddle frames 26 and 27 and the reed 18 can thus be made smaller. The symmetrical arrangement of the shuttle 125 also influences the construction of the same. As shown in Figures 5 and 6, 2 is the shuttle body and 28 indicates a cavity in the same in which the bobbin or cop 30 is placed on a spindle 31 in the usual way. The weft thread protrudes from the shuttle at 32 and 130

the shuttle holders 1 are provided with long narrow slits 33 in the front walls so that the eye or opening through which the weft protrudes will be left uncovered when the shuttle is in the holder.

The shuttle holders should be made of light and strong material such as for instance steel plate, so that the power required for the holder motion may be as small as possible. It will be noted that the shuttle should enter the holder easily and be held in the same by the friction between the shuttle and the holder resulting from the weight of the shuttle. Also spring or friction elements can be used and such could be attached to the wall of the shuttle holder in a manner such that the moving shuttle upon entering the holder would engage and force the same against the holder wall. Such elements would thus exert a pressure against the shuttle, which pressure would tend to increase the friction engagement between shuttle and holder so that the shuttle is held more securely in place. The movement of such spring or friction elements could advantageously be utilized for controlling mechanism for stopping the loom such that when the shuttle fails to enter the holder, the loom is automatically stopped. Such stop mechanism could very easily be designed in principle upon the manner employed in present-

day looms taking into consideration the differences that arise owing to the employment of my improved shuttle motion.

In Figure 7 of the accompanying drawings 35 I have diagrammatically indicated the presence of spring elements 29 which act against the shuttle in the manner indicated above. The action of such elements would be released at the moment of the shuttle transfer 40 by suitable mechanism.

Having now particularly described and ascertained the nature of my said invention, and in what manner the same is to be performed, I declare that what I claim is:— 45

In a loom having picking means for actuating a negative shuttle motion, the provision of a loom frame having lateral extensions integral therewith and provided with guides, reciprocatory picking means forming shuttle holders having extending portions and adapted to engage the said guides, levers pivotally mounted on said frame, connecting means between the levers and the extending portions of the shuttle holders, a 50 power shaft journaled in said frame, members connecting said shaft to said levers and actuating means arranged on said shaft to engage said members.

In witness whereof, I have hereunto signed 60 my name.

A. E. NORRMAN.
